Primary Examiner — Cynthia M Chin(74) *Attorney, Agent, or Firm* — Dickinson Wright PLLC(57) **CLAIM**

The ornamental design for a surface design for a pneumatic tire, as shown and described.

DESCRIPTION

FIG. 1 is a view of the lateral surface of a pneumatic tire with the ornamental surface design in an environment of use; and, FIG. 2 is a detailed view of the ornamental surface design of FIG. 1.

The broken line perimeter structure that is shown in FIGS. 1 and 2 surrounding the design indicates the boundaries of the claim and forms no part of the claimed design. The additional broken lines in FIG. 1 represent environmental subject matter and form no part of the claimed design.
